Application July 25, 1935, Serial No. 33,181

In Germany July 23, 1934

7 Claims. (Cl. 34—48)

This invention is concerned with drying cylinder devices in paper making machines and has for its primary object to provide such a device applicable to existing paper making machines and retaining the usual arrangement of drying cylinders but with elimination of drying felts.

The drying of mechanically produced paper is carried out in paper making machines of usual design in such a way that the paper web, on leaving the presses with a moisture content of about 10 40 to 50 per cent, is led through a long series of drying cylinders arranged in subordinate groups, said cylinders being partly surrounded by an endless blanket of drying felt, for the purpose of 15 pressing the paper or the paper pulp against the heated surfaces of the cylinders. Such a set of drying cylinders forms in the structure of a paper making machine a basic arrangement defining the chief lines of the structural arrangement of 20 such a machine owing to the great number of drying drums and their driving means which have to be mounted in the frame. According to one known arrangement additional drying devices are included depending on the use of a drying felt 25 which has to be brought back to a dry state by heating both on its upper and lower faces, in which arrangement also it is necessary to arrange scrapers on the unwrapped peripheral surface of the drying cylinders. In order to render unnecessary the provision of a drying felt extending 30 over the whole width of the paper pulp web it has been suggested to effect the drying by means of a stationary system of heating pipes replacing the revolving drying cylinders. This is achieved 35 by conducting the web of paper pulp to be dried over drums rotating independently in the neighbourhood of the heating pipes with the assistance of narrow feeding felt strips, care being taken to prevent direct contact of the material with 40 the heating surface of the pipe. Such an arrangement is not well adapted to the drying of paper pulp with reduction of the drying temperature on the surface of the drum, and its adaptation to the drying mechanism of an existing paper 45 making machine would involve an entire structural transformation of the machine by eliminating drying cylinders.

According to my present invention as distinguished from previously known arrangements the drying equipment is arranged so that it may be used in an existing paper making machine without the use of drying felts and retaining substantially the arrangement of drying cylinders 50 usual in paper making machines. The invention consists in that each of the revolving drying cylinders is surrounded by a strainer perforated jacket wall spaced a small distance from the cylinder body, and that, at the lines of engagement and departure of the paper pulp web, spring

pressed guide cylinders or rollers are provided which may replace the usual guide rollers conducting the drying felt to the cylinders. The increase in cylinder diameter involved by providing perforated jackets may be also adapted to the line of contact with the guide rollers. Further the annular space between the perforated jacket wall and the body of the drying cylinder is used for the purpose of exchanging the drying air and for the removal and/or storage of the wet steam, 15 said purposes being achieved by blowing dry, warm air through adjustable air nozzles directed towards the perforated jacket wall in the region of the free circumferential portion lying between the guide rolls.

Narrow guide strips are preferably arranged as accessories at the non-perforated margins of the cylinders to render possible, if necessary, the setting of a paper web on the cylinders. Said guide strips are kept in movement owing to the 20 rotation of the drum and are shiftable in axial direction by means of an engaging and disengaging device.

A part of a drying plant or section according to the invention is illustrated in Fig. 1 in sectional elevation. Fig. 2 shows a side view partly in section.

Fig. 3 is a side view showing the spring pressed roller.

A drying cylinder 1 heated in known manner 30 is provided with a finely perforated jacket wall 2, e. g. made from copper, said wall being spaced at a distance from the body of the drying cylinder, whereby the heat operates on the paper pulp web 3 not as hitherto by conduction, but by 35 radiation. The jacket wall 2 is connected by flanges 4 to the body of the drying cylinder, so that between said cylinder body and the wall an annular space 5 closed at its ends results, from which the generated steam may escape through 40 the perforation of the said wall 2. The paper pulp web is conducted round the jacket wall 2 in a manner known in drying devices and is held thereon with a slight spring pressure by means of 45 rotatably mounted guide rollers 6.

Near the part of the wall 2 not wrapped by the paper web pipes with nozzles 7 are arranged transversely to the paper web through which 50 warm, dry air is blown into the annular space 5.

By such an arrangement of the drying means or section according to the invention, all defects accompanying the previous employment of the drying felts and scrapers are removed. There is no need to apprehend sticking or burning of the paper pulp web on the jacket wall 2 heated 55 by radiation only, with all inherent disadvantageous results affecting the quality of the paper and an indisturbed working. This is also assisted by warm air being blown into the annular space 5 which ensures an easy removal of 60

the paper pulp web from the wall 2, so that the latter may be cleaned if need arises by a simple brushing.

The warm air blown by means of the nozzles 7 into the annular space 5 also provides a control of the heating action exerted by the drying cylinders and thereby permits higher velocities of the paper making machines simultaneously with the highest quality of paper. The air blown 10 into the annular space 5 effects not only a supplementary drying action by supplying heat but it assists drying also by quickly carrying away from said annular space 5 any water vapor formed therein, so that in said space there is 15 a practically uninterrupted presence of dry air capable of absorbing vapor. The arrows in Fig. 1 indicate the admission of the warm air to the jacket space and the discharge of warm air and water vapor therefrom.

20 The consumption of heat energy in the drying section or plant arranged according to the invention is essentially lower, because there is no carrying off of moisture stored by drying felts, these having been eliminated.

25 In order to allow the paper web to be arranged on the jacket wall 2 at the beginning of the work, or to provide against tearing of the edge of the paper web, narrow guide strips 8 may be provided. These strips are moved by the rotating cylinders and if required they may be shifted endwise into the range of the width of the paper web by means of shifter devices 9.

The jacket wall 2 is advantageously supported by annular spacing members 10, provided with 35 apertures parallel to the axis of the cylinder.

A spring pressed roller is illustrated in Fig. 3 of the drawing. The roller 6 bears with its axle or shaft 16 in sliding like blocks 15 which are held between helical springs 17 and 18. The spring 18 is located between the base of a standard 12 attached to the framework 11 of the cylinder and the block 15, whereas the helical spring 17 is located between the block 15 and a slider 19 slidably mounted similar to the block 15 between the legs 13 of the standard 12. The free ends of the legs 13 are connected by a bridge 14 having a boring the wall of which is provided with screwing seat. Through this latter passes a screw bolt 20 the inner ends of which 40 act upon the slider 19, so as to move the latter inwardly between the legs 13 or in a reverse direction. In this way the pressing action of the roller 6 may be regulated.

For more easily removing the roller from the cylinder the slider 19 bears a rotatable hook like member 21 the hook like end of which may be swung in to embrace the shaft 16 of the roller, so that by turning the screw bolt 20 in the required direction the roller 6 is lifted from the 55 cylinder.

60 What I claim is:

1. Feltless drying cylinder equipment for drying the web in paper making machines comprising for each drying cylinder a perforated jacket wall spaced from and surrounding the body of the cylinder, spring pressed guide means provided at the lines of engagement and departure of the paper pulp web with and from said wall, and air supplying means arranged between said 65 guide means for blowing dry warm air into the annular space between said jacket wall and cylinder body.

2. Feltless drying cylinder equipment for drying the web in paper making machines comprising for each drying cylinder a perforated jacket wall spaced from and surrounding the body of the cylinder, spring pressed guide rollers provided at the lines of engagement and departure of the paper pulp web with and from said wall, and air supplying nozzles between said guide rollers for flowing dry, warm air into the annular 10 jacket space.

3. Feltless drying cylinder equipment for drying the web in paper making machines comprising for each drying cylinder a perforated jacket wall spaced from and surrounding the body of the cylinder, spring pressed guide means provided at the lines of engagement and departure of the paper pulp web with and from said wall, air supplying means between said guide means for blowing dry, warm air into the jacket space, and perforated distance pieces between the cylinder body and the jacket wall.

4. Feltless drying cylinder equipment for drying the web in paper making machines comprising a revolving drying cylinder having a perforated jacket wall spaced from and surrounding the body of the cylinder, spring pressed guide means provided at the lines of engagement and departure of the paper pulp web with and from said wall, air supplying means between said guide means for blowing dry, warm air into the jacket space, an endless running guide strip adapted to lap around the ends of the guide rollers and jacketed cylinder uncovered by the web, and means for shifting said strip axially of said rollers and cylinder.

5. Feltless drying cylinder equipment for drying the web in paper making machines comprising a revolving drying cylinder having a perforated jacket wall spaced from and surrounding the body of the cylinder, spring pressed guide means provided at the lines of engagement and departure of the paper pulp web with and from said wall, air supplying means arranged between said guide means for blowing dry, warm air into the jacket space, perforated distance pieces between the cylinder body and the jacket wall, an endless running guide strip adapted to lap around the ends of the guide rollers and jacketed cylinder uncovered by the web, and means for shifting said guiding strip axially of said rolls and cylinder.

6. Feltless drying cylinder equipment for drying the web in paper making machines comprising a revolving drying cylinder having a perforated jacket wall spaced from and surrounding the body of the cylinder, spring pressed guide rollers provided at the lines of engagement and departure of the paper pulp web with and from said wall, air supplying nozzles arranged between said guide rollers for blowing dry, warm air into the jacket space, perforated annular distance pieces between the cylinder body and the jacket wall, an endless running guide strip adapted to lap around the ends of the guide rollers and jacketed cylinder uncovered by the web, and means for shifting the guide strip axially of said rolls and cylinder.

7. Feltless drying cylinder equipment according to claim 1, in which the air supplying means is adjustable.

ERNST SCHMIDT.
